(57) **CLAIM**

The ornamental design for a sock slot, as shown and described.

DESCRIPTION

FIG. 1 is a top plan view of a sock slot showing my new design;

FIG. 2 is a left side elevation view thereof;

FIG. 3 is a front elevation view thereof;

FIG. 4 is a right side elevation view thereof;

FIG. 5 is a bottom plan view thereof;

FIG. 6 is a top right perspective view thereof; and,

FIG. 7 is a top right perspective view thereof in use with a pair of socks.

The broken line showing of a pair of socks is for environmental purposes only and forms no part of the claimed design.
